[57] CLAIM

The ornamental design for an auxiliary rearview mirror, as shown and described.

DESCRIPTION

FIG. 1 is a perspective illustration of the auxiliary rearview mirror shown mounted to an existing automobile rearview mirror;

FIG. 2 is a front elevation view of the auxiliary rearview mirror of FIG. 1;

FIG. 3 is a right-side elevation of the auxiliary rearview mirror of FIG. 1;

FIG. 4 is a left-side elevation of the auxiliary rearview mirror of FIG. 1;

FIG. 5 is a plan view of the auxiliary rearview mirror of FIG. 1;

FIG. 6 is a rear elevation view of the auxiliary rearview mirror of FIG. 1; and,

FIG. 7 is a perspective illustration of two auxiliary rearview mirrors of FIG. 1 mounted to an existing automotive rearview mirror.

The broken line showing of a conventional automobile rearview mirror in FIGS. 1, 5 and 7 and the second auxiliary rearview mirror in FIG. 7 of the drawing is for illustrative purposes only and forms no part of the claimed design.
